APPARATUS FOR ROLLING SHEET METAL

George R. Goldthwaite, South Easton, Mass., assignor to B. F. Sturtevant Company, Boston, Mass.

Application May 26, 1938, Serial No. 210,175

7 Claims. (Cl. 113—52)

This invention relates to apparatus for the manufacture of fan inlets and the like and relates more particularly to methods and apparatus for rolling fan inlets from metal sheet.

5 Fan inlets for efficient air flow have curved portions providing stream-line air flow into the rotors of fans and have straight portions for attachment to the fan casings. In the past, it has been customary to form the inlets from metal sheet by the use of dies or to form the inlets by spinning where the scale of production has not justified the expense of dies. Both these methods are very expensive for if dies are used, a different die for each size of inlet is required and if the inlets are formed by spinning, the man hours required are excessive.

10 This invention provides apparatus for the economic quantity production of fan inlets and the like of any desired size. A single machine cheaply and quickly provides fan inlets of many sizes. In the practice of the invention, a central circular opening is cut from a flat metal sheet. The edges of the circular opening are then forced outwardly in curved lines away from the plane of the flat sheet to assume the desired shape.

15 In one embodiment of apparatus for the practice of the invention, the work sheet is rotated and a rotatable roller having surfaces conforming to the desired curve, is forced against the edges of the circular opening which move along the surface of the roller and assume the desired shape.

20 In another embodiment of apparatus for the practice of the invention, the work sheet is held stationary and the work forming roller is forced against the edges of the circular opening while at the same time it is moved in a circular path of expanding diameter.

25 An object of the invention is to roll metal sheet to form an apertured sheet with outwardly curved inner edges. Another and more definite object of the invention is to roll fan inlets from metal sheet.

30 Other objects of the invention will be apparent from the following description and from the drawings.

The invention will now be described with reference to the drawings of which:

35 Fig. 1 is a view in side elevation of one embodiment of apparatus for the practice of the invention utilizing a revolving work table and a movable form;

40 Fig. 2 is a plan view looking downwardly upon the turret type table of Fig. 1, and shows a centrally perforated metal sheet bolted down upon

a fixed work table ready for the application of the forming roller of Fig. 1;

45 Fig. 3 is a plan view looking downwardly upon the roller assembly of Fig. 5;

Fig. 4 is a side elevation looking from the left, 5 of the roller assembly of Fig. 5;

Fig. 5 is a cross-sectional view through the roller assembly and work table of Fig. 1;

Fig. 6 is an elevation view with the work and work table section and illustrates the roller of 10 Figs. 1—5 as having advanced through partial formation of a fan inlet;

Fig. 7 is a view similar to Fig. 6 except that the roller has advanced to complete the formation of the fan inlet;

Fig. 8 is a cross-sectional view in side elevation of another embodiment of apparatus for the practice of the invention, in which the work sheet is fixed against transitional movement and the work forming roller is advanced in a circular 20 path of expanding diameter against the work sheet;

Fig. 9 is a view of a rotatable work forming roller similar to the work forming rollers of Figs. 1—8 inclusive except that it is provided with two 25 auxiliary work pressure rollers instead of the one shown by the preceding figures;

Fig. 10 is a side elevation of a fixed non-rotatable form which could be used to replace the forming rollers of the preceding figures as where 30 the forming of the work is less difficult;

Fig. 11 is a view similar to Fig. 10 except that the form is equipped with a plurality of small rollers for lessening friction of the work against the form;

Fig. 12 is a side elevation of another embodiment of a work forming roller having a smaller radius of curvature at its work entering portion, and

Fig. 13 is a side elevation of another embodiment of a work forming roller having a plurality of superimposed rotary portions for lessening the friction of the work.

45 Referring first to Figs. 1 to 7 inclusive, the formation of fan inlets by advancing a forming roller against a fixed work sheet will be described.

The metal sheet 15 has cut from it, the circular central opening 16 preferably before being placed upon the turret type work table 17. The work sheet 15 is perforated at several points around its outer edges to receive the bolts 18 which clamp it between the annular rings 19 and 20 and to the table 17.

50 The rotatable forming roller 21 extends from above into the opening 16 and the lower spacing 55

ring 28 is so selected that it spaces the work sheet 15 above the table 17 so that the edges of the circular opening 16 are in alignment with and substantially tangential to the lower curved portion 5 of the roller 21 as shown most clearly by Fig. 5.

The outer surface of the roller 21 has a concave curvature conforming to the curved outline it is desired for the curved portion of the fan inlet to assume so that as the roller 21 is forced to 10 the right (facing the drawings) against the work sheet 15, the latter is forced to follow the outline of the roller 21 to take the shape shown by Fig. 6 and if the forming is continued, to take the shape shown by Fig. 7.

15 The details of the assembly of the roller 21 and of the mechanism of its movement will now be explained with reference to Figs. 1 to 5 inclusive. The roller 21 referring first to Fig. 5 is rotatably mounted upon the shaft 22 through the intermediary of the roller bearings 23. The shaft 22 has an enlarged square upper portion 24 which is clamped to the carriage member 25 by the members 26 and bolts 27.

20 The carriage member 25 is slidably mounted upon the horizontal guides 28, the ends of which are supported in the frame 29. The rotatable threaded rod 30 extends through the carriage member 25 and is adapted to be rotated through the usual gears (not shown) in the gear box 31.

25 The rod 30 may also be rotated by hand by placing a crank upon the extension 32 provided for that purpose. The carriage member 25 contains the usual internally threaded gear (not shown) 35 around and in mesh with the teeth of the threaded rod 30 and affixed to the carriage member 25, so that rotation of the rod 30 moves the carriage member from left to right (facing the drawings) when the work sheet 15 is being acted 40 upon by the roller 21. The details of the gear within the carriage member 25 and of the gear train in the gear box 31 are well known to those skilled in the art and will not therefore be illustrated or described in detail.

45 The support 34 is mounted upon an enlarged portion 33 of the shaft 22 and the roller supporting member 35 is attached to the support 34 by the pivot bolt 36 and by the removable rod 37. The auxiliary pressure roller 38 is supported 50 upon the ball bearing 39 around the shaft 40 of the member 35 and serves to press the work sheet against the work forming roller 21 at its entrance thereon. By removing the rod 37 the member 35 may be swung out of the way by movement 55 around the pivot bolt 36 to the position shown in dash-dot outline by Fig. 7.

60 In forming fan inlets and the like by the embodiments of Figs. 1 to 7 inclusive, the shaft 41 of the turret type table 17 is rotated as it is customary to rotate turret tables and this causes the work sheet 15 to rotate around the work forming roller 21. The roller is then advanced by rotation of the threaded rod to the right (facing the drawings) and its lower portion first 65 rides under the inner edges of the work sheet 15. The auxiliary roller 38 presses downwardly upon the work sheet at its first points of contact with the roller 21 and causes the sheet 15 to follow the curved outline of the roller as it is 70 advanced against the sheet. The roller 21 freely rotates about the bearing 23 under the rotative action of the work sheet to lessen friction and the power required for the rolling operation. Fig. 5 illustrates the position of the work sheet and 75 the rollers, etc., at the beginning of the rolling

operation. Fig. 6 illustrates a fan inlet, the curved portion of which has been rolled through an angle of substantially 90°. Fig. 7 illustrates a fan inlet, the curved portion of which has been rolled through an angle of substantially 120°.

5 After the rolling operation is completed, the member 35 is swung out of the way; the roller 21 removed by removal of the bolts 27 and member 28, and the fan inlet removed after removal of the bolts 18 and ring 19.

10 Fig. 8 of the drawings illustrates another embodiment of apparatus for the practice of the invention. In this embodiment, the work sheet is held stationary and the work forming roller is moved around a circular path of expanding 15 diameter to form the curved portion. In this embodiment, the work sheet 15 rests upon the ring 45 which is bolted to the frame 46. The ring 47 rests upon the work sheet and is pressed against same to hold same immovable by the pistons 48 20 which are forced by compressed air in the cylinder 49 attached to the overhead frame 50, against the ring 47.

25 The shaft 22 of the roller 21 has a threaded lower end upon which the nuts 51 are screwed to hold the shaft in the movable carriage member 52. The member 52 has a lower portion 53 which is tapped and threaded to receive the threaded rod 54 so that rotation of the rod 54 causes transitional movement of the carriage member 52. The rod 54 also supports the carriage member 52. The rod 54 is rotated through the gears 55 and 56, the shaft 57, the gears 58 and 59 and the shaft 60, from gears in the usual feed control 30 box 61. The rods 54 may also be rotated by the hand wheel 62.

35 The threaded rod 54 is supported at both ends by the rotatable members 63 which is attached to the outer hollow shaft 64 within which the shaft 57 rotates. The shaft 64 is attached to the gear 65 and is rotated from a motor (not shown) by the gear 66. The member 63 is rotatably seated upon the block 67 and is supported thereby. The block 67 has an extension 68 which is tapped and threaded to receive the threaded shaft 69 45 which in turn is rotated by the gears 70 and 71, shaft 72, and hand wheel 73 to raise and lower the block 67 and through it, the threaded shaft 54 and the carriage member 52 and the roller 21.

40 In operation, the work forming roller 21 is rotated in a circle in the center of which is the shaft 57. This rotation is affected by rotation of the member 63 which supports the threaded shaft 54 and the carriage member 52. As previously explained, a motor or gear train (not shown) rotates the gear 66 and this rotates the gear 65 and shaft 64 to which the member 63 is attached. During this rotation of the work forming roller 21 around the circumference of a circular path, it is advanced against the inner edges 60 of the work sheet by rotation of the threaded shaft 54 by the gears 55 and 56, the shaft 57, gears 58 and 59, shaft 60 and the gears in the control box 61.

65 It is thus seen that the work forming roller in the embodiment of Fig. 8 advances while moving around the circumference of a circle, against the inner edges of the work sheet which are bent upwardly to follow the curved outline of the roller.

70 The gears which rotate the roller 21 around the circumference of a circle and the gears which advance the roller against the work sheet may be coordinated and may be driven from the same source under either manual or automatic con- 75

trol. These two sets of gears may also be driven separately and independently.

When the rolling of the fan inlet or the like is completed by the embodiment of Fig. 8, the pistons 48 are retracted by the cylinders 49, the ring 47 removed and the fan inlet lifted off the ring 45. This embodiment has the advantage that since the work sheet is stationary, it can be easily held down by the pistons of the compressed air cylinders, enabling the work to be handled faster.

Fig. 9 illustrates another embodiment of an auxiliary pressure roller arrangement which may be used with the rollers 21 of the previously described apparatus. In this embodiment an additional auxiliary roller is mounted in the member 35 with its shaft at right angles to the shaft of the usual pressure roller 38. This presses the work sheet against the roller 21 when it has reached an advanced position. This arrangement is desirable where relatively large size inlets are desired.

Fig. 10 illustrates a form which may be substituted for the rollers 21 of the previously described apparatus. This device is less desirable because it is less rugged and because of the friction resulting from its use.

Fig. 11 illustrates an improved form of the device of Fig. 10 having a plurality of rollers 75 so arranged that they will rotate when the work rolling form and the work are revolved relative each other.

Fig. 12 illustrates another embodiment of a work forming roller having a smaller radius of curvature at its lower portion and may be used for forming curved portions having different radii.

Fig. 13 illustrates another embodiment of a work forming roller having a plurality of superimposed rotary sections. Since the tendency of different portions of the work forming rollers is to rotate at different speeds when in contact with the work sheet, the use of this embodiment may result in less friction in the contact between the work forming roller and the work sheet and may result in less strain in different portions of the curved metal. The auxiliary pressure roller 74 is also illustrated as placed at an angle less than 90° to the auxiliary roller 38.

While the formation of fan inlets has been described in the foregoing, the invention is applicable to fan outlets and to other devices.

While several embodiments of apparatus for the practice of the invention have been described for the purpose of illustration, it should be understood that other apparatus and arrangements of apparatus may be suggested by those skilled in the art without departing from the spirit of the invention.

What is claimed is:

1. Apparatus for forming articles from an apertured sheet, comprising a work table, means forming a surface upon said table for supporting the underside of an apertured sheet, a sheet forming roller having a concave outer surface which curves towards and away from the roller axis, and normally supported with said axis at substantially a right angle to said first mentioned surface, and with its work receiving surface within said supporting means and in alignment with said first mentioned surface, means for rotating said table around said roller, and means for simultaneously therewith advancing said roller in a substantially straight line perpendicular to its axis and with its work receiving surface in align-

ment with said first mentioned surface, from the center of said supporting means towards an edge of said table, for forcing the inner edge of said sheet along the surface of said roller.

2. Apparatus for forming articles from an apertured sheet, comprising a work table, means for supporting an apertured sheet upon said table, a sheet forming roller having a curved surface and supported with its axis at substantially a right angle to the work receiving surface of 10 said table and with its work receiving surface within said means, a work pressure roller supported with its outer surface spaced a relatively small distance from said work receiving surface of said sheet forming roller for pressing said sheet against said work receiving surface during the operation of said apparatus, means for rotating said table around said sheet forming roller, and means for simultaneously progressively advancing said forming roller in a substantially 15 straight line perpendicular to its axis from the center of said sheet supporting means towards an edge of said table for forcing the inner edge of said sheet along the curved surface of said forming roller. 25

3. Apparatus for forming articles from an apertured sheet, comprising a work table, means forming a surface upon said table for supporting the underside of an apertured sheet, a sheet forming roller having a concave outer surface 30 which curves towards and away from the roller axis, means for supporting said roller with said axis at substantially a right angle to the work receiving surface of said table and with its work receiving surface within said supporting means and normally in alignment with said first mentioned surface, means for rotating said roller supporting means and said table relative each other, and means for simultaneously therewith advancing said forming roller and said table in a substantially 35 straight line perpendicular to said axis and with the work receiving surface of said roller in alignment with said first mentioned surface, towards each other for forcing the inner edge of said sheet along the curved surface of said forming roller. 40

4. Apparatus for forming articles from an apertured sheet, comprising a work table, means for supporting an apertured sheet upon said table, a sheet forming roller having a curved outer surface, means for supporting said roller with its axis at substantially a right angle to the work receiving surface of said table and with its work receiving surface within said means, a work pressure roller supported with its outer surface spaced a relatively small distance from said work receiving surface for pressing said sheet against said work receiving surface during the operation of said apparatus, means for rotating said roller supporting means and said table relative each other, and means for simultaneously progressively advancing said forming roller and said table in a substantially straight line perpendicular to said axis towards each other for forcing the inner edge of said sheet along the curved surface of said forming roller. 50

5. Apparatus for forming articles from an apertured metal sheet, comprising a work table having a central opening, means forming a surface upon said table for supporting the underside 55 of an apertured sheet around said opening, a sheet forming roller having a concave outer surface which curves towards and away from the roller axis, means for supporting said roller with said axis at substantially a right angle to the work receiving surface in alignment with said first mentioned surface, means for rotating said table around said roller, and means for simultaneously therewith advancing said roller in a substantially straight line perpendicular to its axis and with its work receiving surface in align-

- work receiving surface of said table, and with its work receiving surface within said opening and normally in alignment with said first mentioned surface, and means for rotating said roller supporting means and for simultaneously advancing same in a substantially straight line perpendicular to said axis and with the work receiving surface of said roller in alignment with said first mentioned surface, from the center of said sheet supporting means towards an edge of said table for forcing the inner edge of said sheet along the curved surface of said forming roller.
5. Apparatus for forming articles from an apertured metal sheet, comprising a work table having a central opening, means for supporting an apertured sheet upon said table around said opening, a sheet forming roller having a curved outer surface, means for supporting said roller with its axis at substantially a right angle to the work receiving surface of said table, and with its work receiving surface within said opening, a work pressure roller supported with its outer surface spaced a relatively small distance from said work receiving surface for pressing said sheet 10 against said work receiving surface during the

operation of said apparatus, and means for rotating said roller supporting means and for simultaneously advancing same in a substantially straight line perpendicular to said axis from the center of said sheet supporting means towards an edge of said table for forcing the inner edge of said sheet along the curved surface of said forming roller.

6. Apparatus for forming articles from an apertured metal sheet, comprising a work table having a central opening, means for supporting an apertured sheet upon said table around said opening, a sheet forming roller having a curved outer surface, means for supporting said roller with its axis at substantially a right angle to the work receiving surface of said table and 15 with its work receiving surface within said means, means for rotating said roller supporting means and said table relative each other, and means for simultaneously progressively advancing said forming roller and said table in a substantially straight line perpendicular to said axis towards each other for forcing the inner edge of said sheet along the curved surface of said forming roller.

7. Apparatus for forming articles from an apertured sheet, comprising a work table, hydraulic means for supporting an apertured sheet upon said table, a sheet forming roller having a curved outer surface, means for supporting said roller with its axis at substantially a right angle to the work receiving surface of said table and 15 with its work receiving surface within said means, means for rotating said roller supporting means and said table relative each other, and means for simultaneously progressively advancing said forming roller and said table in a substantially straight line perpendicular to said axis towards each other for forcing the inner edge of said sheet along the curved surface of said forming roller.

GEORGE R. GOLDTHWAITE. 25
